UNITED STATES PATENT OFFICE.

ARTHUR H. ROGERS, OF SPRINGFIELD, MASSACHUSETTS.

DESIGN FOR A PENCIL-STAMP.

SPECIFICATION forming part of **Design No. 12,787**, dated **February 21, 1882.**

Application filed January 10, 1882. Term of patent 3½ years.

To all whom it may concern:

Be it known that I, ARTHUR H. ROGERS, a citizen of the United States, residing at Springfield, in the county of Hampden and State of Massachusetts, have invented and produced a new and original Design for a Pencil-Stamp, of which the following is a specification, reference being had to the accompanying drawings, forming part thereof.

Figure 1 is an inverted view of my newly-designed pencil-stamp. Fig. 2 is a view of the cover for said stamp. Fig. 3 is a similar view to Fig. 1, but showing the face side of said stamp. Fig. 4 is, like Fig. 2, a view of the stamp-cover, but showing the top side thereof.

The leading features of my design consist in making the stamp case *b* with a border of octangular form, and in making that end of the pencil-tube *a* which is attached to the back of the stamp-case *b* of a trumpet-mouth shape. The stamp-cover *c* is made of a like octangular form to said stamp-case *b*.

tangular form, and in making that end of the pencil-tube *a* which is attached to the back of the stamp-case *b* of a trumpet-mouth shape. The stamp-cover *c* is made of a like octangular form to said stamp-case *b*.

I claim—

The design for a pencil-stamp herein shown and described, the same consisting of a stamp-case, *b*, having a border of octangular form, and of the pencil-tube *a*, having the end thereof which is joined to the back of said case of trumpet-mouth shape.

ARTHUR H. ROGERS.
